[57] **CLAIM**

The ornamental design for a combined laparoscopic tool
holder and positioner, as shown and described.

DESCRIPTION

FIG. 1 is a left-front perspective view of a combined
laparoscopic tool holder and positioner showing our new
design, a right-front perspective view being a mirror image;
FIG. 2 is a front elevational view thereof;
FIG. 3 is a rear elevational view;
FIG. 4 is a left side elevational view, a right side view being
a mirror image;
FIG. 5 is a top plan view; and,
FIG. 6 is a bottom plan view.
